UNITED STATES PATENT OFFICE

1,963,456

METHOD AND APPARATUS FOR DRAWING
WIREHerman S. Worthington, Yardley, Pa., assignor
to The American Steel and Wire Company of
New Jersey, a corporation of New Jersey

Application May 24, 1933, Serial No. 672,703

3 Claims. (Cl. 205—16)

This invention relates to improvements in a method and apparatus for drawing wire, and more particularly to that type of wire which is known as "dead-cast". That is to say, wire that is drawn, or "cast", without lateral deflection, in order that a complete convolution, or turn, thereof when removed from the wire drawing block and supported in a vertical position with the two ends at the lowest point will have an axis, or 10 center line, in a vertical plane.

One object of the present invention is to provide a novel method and apparatus for drawing wire which includes initially winding the same for a few convolutions on a wire drawing block, 15 and in diverting the wire from the block for an intermediate "dead-casting" operation, after which it is returned to the block.

Another object is the provision of a novel method and apparatus for obtaining "dead-cast" 20 wire, together with means for adjusting the desired final diameter of the coil.

These and other objects will appear after referring to the drawing, in which:

Figure 1 is a plan of the apparatus of the 25 invention.

Figure 2 is a sectional elevation on the line II—II of Figure 1.

Figure 3 is an enlarged detailed elevation of 30 part of the apparatus.

Referring more particularly to the drawing, the numeral 2 designates a wire drawing frame upon which there is mounted a rotating wire drawing block 3. A conventional wire drawing die 4 is mounted upon a die holder 5, which is 35 suitably secured to the wire drawing frame 2.

According to the present invention, a support 40 6 is horizontally slotted, as at 6^a, provided with a vertical shaft 7, and suitably secured to the wire drawing frame. A vertical shaft 8 is mounted for sliding movement in the slot 6^a and a screw 9 is threaded through a portion of the support 6 for adjusting its position relative thereto. The screw 9 is maintained in adjusted position by means of a nut 10, and a nut 12 is threaded on the end 45 of the vertical shaft 8 for securing it against movement after it has been adjusted in the slot 6^a.

A grooved roller 14 is mounted for rotation on the shaft 7, while a relatively smaller grooved roller 15 is similarly mounted on the adjustable 50 shaft 8.

In operation, the wire to be drawn, which is indicated at A, is threaded through the die 4 and secured to the wire drawing block 3 in the well known manner. The drawing block is rotated 55 several times and stopped, after which the several convolutions of the wire wound thereon are loosened and one strand thereof passed around the roller 14.

The roller 15 is adjusted to govern the diameter desired in the coil, which increases as the dis-

tance between the roller and the center of the wire drawing block 3 increases. This adjustment is effected by means of the screw 9, which is locked in position by the nut 10. The nut 12 is then tightened on the shaft 8 in order to maintain the latter in adjusted position. 65

As the wire is wound back onto the wire drawing block 3 from the roller 14, which is in a straight line with the block or, in other words, at a vertical angle of 90 degrees with respect to 70 its axis, it will be "dead-cast" and have the characteristics previously referred to.

While I have shown and described one specific embodiment of my invention, it will be understood that I do not wish to be limited exactly thereto, 75 since various modifications may be made without departing from the scope of my invention, as defined in the following claims.

I claim:

1. Apparatus for producing dead-cast wire 80 comprising, in combination, a wire drawing die, a drawing block, a roller adjacent said drawing block having a return feed angle of 90 degrees with respect to the axis of the block, and a longitudinally adjustable roller associated with said first named roller, said first named roller being operable to receive at least one strand of wire from said block and to return the same directly thereto. 85

2. Apparatus for producing dead-cast wire 90 comprising, in combination, a wire drawing die, a drawing block, a roller adjacent said drawing block having a return feed angle of 90 degrees with respect to the axis of said block, a tension roller for cooperating with said first named 95 roller, and means for adjusting the position of said tension roller with respect to said drawing block, said first named roller being operable to receive at least one strand of wire from said block and to return the same directly thereto. 100

3. Apparatus for producing dead-cast wire comprising, in combination, a wire drawing die, a drawing block, a support adjacent said drawing block, a roller mounted on said support having a vertical return feed angle of 90 degrees 105 with respect to the axis of the block, a horizontal slot in said support, a vertical shaft disposed for movement in said slot, an auxiliary roller mounted on said shaft, means for adjusting the position of said shaft, and means for locking 110 said shaft in adjusted position.

HERMAN S. WORTHINGTON.
